UNITED STATES PATENT OFFICE.

FREDERIC H. EHNTS, OF GERMANTOWN, PHILADELPHIA, PENNSYLVANIA, ASSIGNOR,
BY MESNE ASSIGNMENTS, TO H. W. BUTTERWORTH & SONS COMPANY, A CORPORA-
TION OF PENNSYLVANIA.

LAUNDRY MACHINERY.

Application filed August 13, 1921. Serial No. 492,029.

This invention relates to laundry machinery and more particularly to power driven laundry machinery.

A general object of this invention is to 5 provide an improved construction and arrangement of parts which is economical and readily manufactured.

A specific object of this invention is to provide an improved power transmitting 10 connection which will not jam or easily become disarranged.

A further specific object is the provision 15 of an arrangement whereby portable laundry machinery, such as washing machines, ironing machines, and the like may be used in conjunction with the fixed apparatus such as the stationary laundry tubs now generally found in modern dwellings.

A still further object is the provision of 20 an arrangement whereby such portable laundry machinery may be driven interchangeably from a single source of power.

Other objects will be in part obvious and in part pointed out hereinafter.

25 The invention accordingly consists in the features of construction, combination of elements and arrangement of parts which will be exemplified in the construction hereinafter set forth, and the scope of the application of which will be indicated in the following claims.

In accomplishing the objects of my invention, I preferably provide the fixed apparatus with a source of power, generally an 35 electric motor; and provide a novel arrangement of couplings and housings with which the portable machinery is equipped and adapted for interchangeable connection with the power source.

40 For a more complete understanding of the nature and objects of my invention reference should be had to the following detailed description taken in conjunction with the accompanying drawings in which:

45 Figure 1 shows in side elevation a portable washing machine coupled for use in conjunction with stationary laundry tubs in accordance with my invention;

50 Fig. 2 is a top plan view of the arrangement shown in Fig. 1;

Fig. 3 is a fragmentary side elevation of a power coupling on an ironing machine adapted to be used interchangeably with the washing machine shown in Fig. 1;

Figs. 4, 5, and 6 are detailed views of the 55 power transmitting connections and housings shown for the washing machine in Fig. 1; and

Fig. 7 is a detail of the friction coupling 60 for transmitting power from the motor element.

Referring now to the drawings in which like parts are designated by the same reference characters: A designates a set of stationary laundry tubs such as are customarily built into modern dwellings; 8 is the portable laundry or washing machine which is designed to be used in conjunction with tubs A. The washing machine B is illustrated as one of the well known cylinder type, and 70 has a power coupling C (see Fig. 4) in the housing D in order that it may be driven by power supplied from the electric motor E, which is illustrated in Fig. 1 as secured to the under side of the stationary tubs A. 75

The machine B may be mechanically disconnected from the tubs A merely by withdrawing the housing D from the gear housing G, the manually manipulated ring 10 on housing D being provided to lock both housings together in a manner more fully set forth hereinafter. Accordingly the machine B may be removed at will and replaced by another portable laundry machine; for instance, the ironing machine F, shown in Fig. 3, which has a housing H adapted similarly to co-operate and be coupled to the gear housing G. The housing H is also shown as provided with a manually manipulated ring 10', similar to the one at 10, for securing the housings in coupled relation. 80 85 90

The gear housing G is secured in a stationary manner, preferably to some convenient part of tubs A, as shown in Fig. 1. This housing, as shown in Fig. 4, contains a rotatable member 15 which is the driving member of the power coupling at C. The member 15 is secured on a short shaft 16 journaled in the housing G and carries the beveled pinion 17 which meshes with the beveled gear 18 on the vertical shaft 19, the latter also being journaled in the housing G but at right angles to the other. 95 100

The vertical shaft 19 is driven at reduced speed by the horizontal shaft 20, (see Fig. 7) which is coupled by the friction coupling 21 to the motor shaft 22. The friction coupling shown comprises a disc or pulley 23 keyed 105

or otherwise rigidly secured to shaft 22, as by the set screw 24, and has a facing 25 of friction material, such as leather, fiber, and the like, adapted to abut against and adhere 5 to the inner or friction surface of the bell shaped member 26 which latter is rigidly secured on shaft 20. To increase or otherwise regulate the frictional pressure between facing 25 and member 26, a spring 27 is provided 10 encircling the shaft 22, drawn up by plate 28 and its screws 29 in the member 26; which spring reacts against the disc 23, the reaction urging the frictionally engaging surfaces together and applying a 15 pressure proportional to the tension of the spring, which tension may be adjusted by manipulating screws 29. This arrangement, it will be perceived, while normally transmitting the power of the motor to the shaft 20 19, also permits the slipping of the clutch in the event that any part of the power transmitting connections or machine B become 25 jammed and prevented from turning, whereby by the stripping of gears is avoided.

25 The speed reducing gearing for connecting shaft 19 with shaft 20 so as to be driven thereby is illustrated in broken lines at 30 in Fig. 2 and comprises a worm on shaft 20 and a worm gear on shaft 19. In one aspect 30 of my invention, however, any suitable speed reducing gearing may be employed. As shown, the shaft 19 is a part of the fixed power equipment of the stationary tubs A and rotates in a vertically extending housing 31 of its own, and may be conveniently extended up to be connected with and drive a clothes wringer K. This wringer is conveniently mounted above the tubs A and may be adjusted to various positions with respect 35 to the tubs, as the working conditions may require. In the position shown in the drawing, the wringer is adapted to receive clothes from the washing machine B and deliver them when wrung to its tub A. When the 40 wringer is swung to a second position between the tubs at ninety degrees from the first, it is adapted to discharge the clothes from the first tub and deliver into the second; and when swung to a third position 45 through still another ninety degrees, or one hundred and eighty degrees from the first, it is adapted to discharge clothes from the second tub and deliver to a basket which has been placed before the tubs.

50 55 In order to readily effect the mechanical connecting and disconnecting of the portable laundry machines with the source of power, the casing G is provided with tubular extension 33 (see Fig. 6) which is adapted to project into and telescope with a corresponding tubular formation 34 on the housing D, the extension 33 being provided with a guiding projection co-operating with the slot 35 in housing D. The slot 35, as shown, is preferably 60 longer than ring 10 is wide, in order 65

that the projection 33' (which is higher than slot 35 is deep) may project up beyond the ring 10 and thereby be locked in place. To this end the ring 10 is provided with an offset groove at 36 which when in register with the slot 35, as shown in Fig. 6, permits the projection 33' readily to be slid under the ring back and forth throughout the whole length of the slot 35. When the groove 36 is turned out of register with the slot 35, the handle 37 on the ring being provided for this purpose, the ring 10 acts as a lock to hold the housing D properly coupled to the housing G, i. e., provided the projection 34 has been slid into the slot 35 to a point beyond 80 the ring 10.

In order to accommodate itself readily to variations in the height of the housing D on the detachable machine, the housing G is preferably made vertically adjustable on the shaft 19. To accomplish this the housing G proper is provided with a lower tubular extension 38 which surrounds shaft 19 and is adapted to slide into and telescope with the tubular end 39' of the housing 39 which is 90 fixed with respect to the tubs A and is shown as an extension of the housing which encloses the gearing at 30. Provision, however, is made to hold housing G in fixed position, the adjustment with respect to the detachable machine having once been made. To this end the upper tubular end of housing 39 is split and provided with lugs and a tightening screw 39" for drawing the lugs together whereby to clamp the extension 38 100 and hence the housing G in any desired position. This construction necessitates that gear 18 shall be slidably mounted on shaft 19. Accordingly the shaft 19 has a keyway cut 105 therein as indicated in broken lines at 19' in which may slide the key 18' secured in the gear 18, in order that it may drive gear 18 whatever the position on shaft 19.

Within the housing D, with which the machine B is equipped, is journaled a power 110 transmitting shaft 40. At one end this shaft is provided with a worm 41 adapted to mesh with worm wheel 42 on the cylinder shaft 43 of the washing machine. At the other end, the shaft 40 has the sliding clutch member 115 45 arranged to rotate it, which member comprises the companion portion of the power coupling C detachable from but engageable with the member 15 by reason of the projections 45' and 15' provided respectively on 120 their abutting faces.

When housing G has been locked to housing D and member 45 slid into contact with member 15, the rotation of member 15 will cause projection 15' to engage with projection 45' thereby causing member 45 to be rotated and power to be transmitted thereto. The housings G and D when assembled as described also function as bracing members 125 to support the portable machine in operative 130

position, thus maintaining the clutch members 15 and 45 in operative alignment.

In order to slide member 45 on shaft 40, a rod 46 is provided in the housing D. This rod is rotatably and slidably secured in the housing and has at one end exterior to the housing a handle or manipulating member 47; at its other end a fork shaped member 48 is provided whose prongs 49 engage with an annular groove 50 in the member 45. The rotation of rod 46 is preferably constrained within the limits of a quarter of a turn; to this end it has limiting means comprising the pin 51 thereon adjacent the fork shaped member 48, adapted to engage with a pair of stops 52 which are displaced substantially 90° from each other and are disposed on the member 48 in the path of the arc of travel of pin 51.

By sliding the rod 46 back and forth the clutch members 45 and 15 are made to engage and disengage in order to start and stop the washing machine B. The function for the rotation of the rod 46 is to enable the machine B to be automatically stopped in a predetermined position. To this end the rod 46 is provided with a second pin 61 shown in Fig. 4 as projecting laterally to a point closely adjacent the surface of the worm wheel 42. The pin 61 in this position is adapted to be engaged by the projection 62 protruding outwardly from the surface of wheel 42. This projection, when the wheel 42 is turning counter clockwise will engage pin 61 when in this lateral position and cause rod 46 to slide outwardly and disengage clutch members 45 and 15. The pin 61 is preferably so positioned on the wheel 42 that when rod 46 has been fully drawn out by projection 62 the cylinder of washing machine B will have stopped with its closure (which receives the fabrics to be washed) in its uppermost position, as shown in broken lines at 65 in Fig. 1.

Normally the handle 47 is rotated through 90° out of the position shown in the drawing into a plane perpendicular to the plane of the paper. In this position the pin 61 sticks upwardly as indicated at 61' in Fig. 5. This is the ordinary position of the pin and handle when machine B is running.

From the construction shown it is apparent that by simply manipulating the handle 47, the washing machine B may be started, stopped, or brought to a stop in a predetermined position. Also, by the connection of housings D and G the machine B is connected with its power supply, the ring 10 being manipulated to lock it in place. In like

manner the machine F may be used interchangeably with machine B, by attaching it to the source of power through its gear housing H, the latter being also locked in place by the manipulation of ring 10.

Thus by the above described construction are accomplished, among others, the objects hereinbefore referred to.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described, and all statements of the scope of the invention which, as a matter of language, might be said to fall therebetween.

Having described my invention, what I claim as new and desire to secure by Letters Patent is:—

1. A portable laundry machine adapted to be coupled with a fixed source of power, said machine having power transmitting connections comprising a shaft having a shiftable coupling member, a housing for said connections, a shifting rod in said housing having an exterior handle at one end and a member engaging with said coupling member at the other end, and means controlled by said rod to stop said machine in a predetermined position.

2. A portable laundry machine adapted to be coupled with a fixed source of power, said machine having a propelling gear provided with a projection and power transmitting connections to said gear comprising a shaft having a shiftable coupling member adapted when in one position to be mechanically coupled to said source of power and to be uncoupled when shifted to another position, a housing for said connections, and a rotatable shifting rod in said housing having a handle at one end and a member adapted to engage with said coupling member at the other; said rod having a pin adapted when rotated into the path of the projection on said propelling gear to be engaged thereby for shifting said rod, whereby said machine is automatically stopped in a predetermined position.

In testimony whereof I affix my signature.

FREDERIC H. EHNTS.
